UNITED STATES PATENT OFFICE.

HARVEY C. MUMMERT, OF HOLLIS, NEW YORK, ASSIGNOR TO CURTISS AEROPLANE & MOTOR CO., INC., OF GARDEN CITY, NEW YORK, A CORPORATION OF NEW YORK.

RADIATOR FOR AEROPLANES.

Application filed August 30, 1924. Serial No. 735,104.

My invention relates to radiators for aeroplanes and more particularly to improvements which are adapted to very appreciably reduce the air resistance of the radiator during the translation of the aeroplane thru the air.

In the drawings, wherein the preferred embodiment of the invention is illustrated:

Fig. 1 is a side elevation of the radiator showing its relation to the aeroplane of which the radiator forms a part;

Fig. 2 is a detail side elevation, partly broken away, of the radiator showing in detail its relation to one of the supporting struts of the aeroplane;

Fig. 3 is a plan view, partly in section, of the radiator and its associated streamline casing;

Fig. 4 is a rear end elevation, partly broken away, further illustrating the radiator and its associated casing;

Fig. 5 is a fragmentary view illustrating in detail the radiator shutter operating mechanism; and,

Fig. 6 is a view similar to Figure 5, in which the shutter operating mechanism is viewed from a different angle.

The aeroplane of which the radiator forms a part may be of any desired construction, or, if desired, the radiator may be used on or in connection with other forms of self-propelled vehicles than the aeroplane. In the embodiment of the invention selected for illustration the wings or supporting surfaces of the aeroplane are designated as 10, the fuselage or body as 11, the motor as 12, and the wing struts as 13. The radiator and its associated structure, by means of which its resistance is reduced, is designated as an entirety as 14. Preferably such structure is mounted in proximity to one of the supporting struts 13 whereby it (the strut) provides the radiator support.

The radiator per se may be of any well known construction. As illustrated, it is of the honey-comb type in that it comprises a plurality of separated air and water passages thru which the liquid cooling agent on the one hand and the air on the other hand are adapted to pass to effect the desired interchange of heat. On either side of the radiator 15 water passages 16 are provided. Such passages extend throughout the full length of the radiator and communicate at one end with a header 17, integral with the

radiator, and preferably of streamline form. The header 17 enters into and forms an actual part of the streamline casing 18 within which the radiator 15 is enclosed. Said casing 18 comprises in addition to the header 17 oppositely curved and suitably spaced side walls. By mounting the radiator in the manner indicated, its resistance to forward travel is reduced approximately 60 per cent.

In addition to the header 17 at one end of the radiator a header 19 is provided at its opposite end. This header 19, in view of the fact that it is entirely enclosed in the aeroplane fuselage or body 11, and regardless of its shape, offers no resistance whatsoever. The cooling agent, in its circulation, is withdrawn from the header 19 by means of a pipe 20. From the pipe 20 the cooling agent enters the motor 12 to effectually cool it. From the motor 12 the cooling agent is pumped to and thru the water passages 16 on opposite sides of the radiator, and by means of the water passages is conducted to the header 17, and since the passages 16 are formed in part by the casing sides, obviously the agent is cooled somewhat before reaching the outer end header. From the header 17 the cooling agent enters the radiator proper. The side walls of the casing 18 are preferably made sectional. The forward section, designated as 21, is hinged to the intermediate section, designated as 22, as indicated at 23, and the rear section designated as 24 is hinged to said intermediate section as indicated at 25. Thus connected and arranged, obviously the forward and rear sections 21 and 24 can, if necessary, be adjusted. Between the rear sections 24 of the casing a shutter for the radiator is mounted. The shutter, in the embodiment of the invention selected for illustration, in one position of adjustment constitutes a barrier against the passage of air thru the casing 18 and in a different position of adjustment provides fairing for that portion of the supporting strut 13 disposed between the casing sides. In Figure 3 the flaps 26 which serve on the one hand as a radiator shutter and on the other hand as the strut fairing are best illustrated. Preferably these flaps are fastened along one edge to the strut 13 and suitable operating mechanism 27 is disposed between them to effect the desired adjustment. Such operating mechanism includes an operating rod 27' movable in the direction of the length of the flaps 26 to move the flaps about their respective

tive hinge axes, the rod at one end being carried inside the body 11 of the aeroplane where it is fastened to a bell crank 28, the movement of which may be under the direct control 5 of the pilot.

In operation, the air enters the space between the forward sections 21 of the casing, passes thru the radiator 15, and leaves the casing thru the space between the rear sections 24 thereof when the flaps 26 are in the dotted line position indicated in Fig. 3. When the flaps 26 are spread as indicated by the full lines of Fig. 3, an effective shutter for the radiator is provided. In this latter position it is not necessary that the strut 13 be faired.

While I have described my invention in detail in its present preferred embodiment, it will be obvious to those skilled in the art after 20 understanding my invention, that various changes and modifications may be made therein without departing from the spirit or scope thereof. I aim in the appended claims to cover all such modifications and changes.

25 What I claim is:

1. In combination, a self-propelled vehicle, a casing comprising substantially parallel side walls appropriately spaced to provide openings respectively at the forward end and 30 at the rear end of the casing, a radiator mounted between the side walls of the casing and intermediately of said openings, a support for the radiator enclosed for a portion of its length within said casing, and a shutter 35 for the radiator carried by said support.

2. The combination with an aeroplane, of a radiator mounted in proximity to a structural element of aeroplane, and a shutter for

said radiator comprising hinged fairing pieces fastened to said element, said fairing 40 pieces being relatively movable from a non-shuttering position in engagement one with the other to a shuttering position in which said pieces are widely spaced.

3. In combination, a self-propelled vehicle 45 including a supporting element, a radiator mounted in proximity to said element, a casing within which said radiator is enclosed and between the side walls of which said element extends, and a shutter for said radiator 50 comprising hinged fairing pieces fastened to said element, said fairing pieces being relatively movable from a non-shuttering position in which they fair said element to a shuttering position in which said pieces are 55 widely spaced to respectively engage, in their finally adjusted position, the opposite faces of said casing wall.

4. In combination, a self-propelled vehicle, an open end casing, a radiator mounted with- 60 in said casing intermediately of its opposite open ends, an element of said vehicle carried thru said casing behind said radiator, and a shutter for said radiator comprising hinged 65 fairing pieces fastened to said element, said fairing pieces being movable from a non-shuttering position in which they fair said element by engagement one with the other to a shuttering position in which the opening at one end of said casing is completely closed 70 by spreading said fairing pieces until they respectively engage the opposite inside faces of the casing wall.

In testimony whereof I hereunto affix my signature.

HARVEY C. MUMMERT.
